John Pearce, Granite, Maine

Sectors Patent

The object is referred to in these Sectors Patent and making part of the same, containing a description, table, and drawing of her invention John Pearce himself of his improvement in framing hewing off and becoming a Ship or other Vessel deck which he styles a Sack deck by purchase.

In all whom this patent shall come. It is known that I, John Pearce of Granite, in the County of Lincoln and State of Maine have invented a new and useful improvement in framing hewing, and becoming a Ship or other Vessel deck which I style a Sack deck by purchase and that the following is a full and exact description of the construction of the frame of a ship's deck constructed in the method aforesaid as invented by me, referring to the plan hereto annexed. The lines of the ship are represented on said plan by the word "line" of the ship. A represents the beams extending from side to side the ends of which are hewed to fit to the Chocks. B represents the Sack Chocks hewed and fastened to the beams and sides of the ship as represented in the plan. It may be observed that there may be one or more of these Sack Chocks on each side of the beams, as the ship may happen to be. Convenient. If the ship be so in all two of them may be made and put together equally as strong as a chock of one piece as may be seen at B. C on the plan represents the fitting in blocks between the Sack Chocks. There may be either one or two of these between the beams as may be most convenient. It makes no difference with the strength. If they be made in one piece it will be observed in the plan that they must be made with a shoulder to fasten the Sack Chocks. D represents they being driven in between the Sack Chocks and the fitting in blocks neatly and closely fastening the whole together so as a vacuum that it is impossible to make a hole in the slightest degree. To prevent this bay from starting off, it is driven a spike through the beam into the end of it. E represents a brace hewed from off the beam end of the Sack deck beam it being much more easily obtained

7/4/14

as almost any timber will make one, and is also much better and stronger than a common beam block.

One refers to the bolts which is made either of iron or
steel in square headed & English iron and be riveted on Copper or iron
plates to the bottom of the Deck. These bolts must not be more than two
thirds the size of bolts required for beams framed with knees in the usual
way. The advantage of framing the deck of a ship with straight beams in
the manner of the Sack structure may purchase instead of knees on the
knots the timber is much less expensive and more easily obtained. Secondly
it is very much stronger and easier work but need not contain pine
as long as the wood remains sound. To frame a deck in this manner
take a piece of timber say four feet long, four inches wide and nine
inches thick (according to the size of the ship) and split it obliquely
thus then put the straight grain side on to the end of the beam with
tome locks 1/4 inch deep, lay it on to the beam (into which locks have been
cut in the same way) before the beam is put into the Yoke. The wood thus
prepared at the beam is call a Sack block. One of these must be on each
side of the beam at both ends. It will be readily perceived that they are
much cheaper & more easily obtained than knees & when bolted as on the
plan must be much stronger. Between the block on one beam and that on
the other put in so that it will a fitting in block. This may either be one
as the pieces of timber are may be of pine or any other soft wood
being equally strong or not. The outer one should be of four a foot & say
three inches thick and the inner one eight inches thick made to lay in
a shoulder cut into the Sack block. A space should be left between
the end of the fitting in block and the Sack block for a key which
should be made with half an inch drift.

Having prepared the fitting in blocks
as before mentioned I proceed to bolt them with four bolts extending
from the outside of the ship one on each side and being riveted
upon steel plates of iron by turning across and let into the fitting in
blocks so that they cannot split. Then drive the key taught aside
and drive it so as to let the joint knock & knock and secure the end

of the log with a spike. When this is done it will be found that the side of the log will remain close to the beam and cannot be opened. Start 25 then proceed to bolt the ship as the plan describes. Then the two bars will be a short bolt from the outside of the ship through the Deck Chocks in the end of the beam so that they catch each other in going through the deck. Set them in iron plates on the inside. Then drive the iron and a bolt through the chocks and beams. Lay two or three bolts through each end so you will not strain them.

In bolting this driven spring lock it will be seen that the strain can strain them through and come through the inside plates and riveted or set in a plate extending quite across the chock. You can not the slightest give to the work for more strain in the log. The tighter the work draws up the common wood of having a log set. We are compelled to use these with much sap & many times with small ones which can hardly be bolted without splitting. In this way we can easily obtain timber from sap.

These are difficult to be obtained and are expensive. Chocks are got out of pieces of timber which never be wasted or thrown away & cost comparatively nothing. If your timber be small you can bolt chock on chock & make as strong work as if your timber were large. When a beam is found in the log way if it be it is difficult to take it out as well as expensive. In this way there is no difficulty & if the end of the beam be it can be sawed off & lay chocks & spike on the beam and then be layered up so they are solid all the without disturbing the deck. When a log is placed in this way I have found from actual try & point out that it will hold that in a high deck log of the broadest two or three hundred feet beam I have made by driving my stanchions over & taught under the beam to more than half an inch.

This method is not only much stronger but decidedly handier than any other. The work being square with the corners which because of almost all farms and houses there much stronger than iron bars & cost them about half price.

on these bolts alone without locks or cleats. This method is particularly useful in the armed Yacht where great strength is wanted; the beams being so secured to the sides so that the ship cannot in any event sprue. The Standard knees & hanging 8 Flag go knus 8c run in cleats & deck. Ships which take up to much room are all dispensed with in this plan & the ship still stronger. I have still in Yacht the present drawn upon this plan & the idea of the difference in strength until tried the experiments. The fact is the deck cannot stand. The wood must either take or break. Upon this plan Soft wood it is believed is nearly as quite as good as hard wood.

The objection to soft wood has been that it would not hold the fastenings. In this method that is not an objection to the wood. It is locked and cleated together so that it is strong without fastenings. It does not require more iron or copper than the usual method.

I would recommend that all the chocks be put together with white lead or varnish in the joints & then the key area slipped in lead or varnish. It will be seen that a breast chock made in this way may be extended by being locked together as far as you please & payed to the forward beam making the bow of your ship stronger. By this method there is no necessity of reducing the ends of the beams to the largest they are at the most the latter. If the ends of the beams are large they may be locked to the standard piece of timber now be required for the chocks.

With best regards
John Deane
